UNITED STATES PATENT OFFICE.

MILFORD J. MCINTYRE, OF GOWANDA, NEW YORK.

EMERGENCY CUT-OFF.

1,090,221.

Specification of Letters Patent. Patented Mar. 17, 1914.

Application filed March 8, 1913. Serial No. 752,936.

To all whom it may concern:

Be it known that I, MILFORD J. MCINTYRE, a citizen of the United States, residing at Gowanda, in the county of Cattaraugus and State of New York, have invented certain new and useful Improvements in Emergency Cut-Offs, of which the following is a specification, reference being had therein to the accompanying drawing.

This invention relates to safety valves for pipe lines and has for its object the production of a simple and efficient emergency shut-off which will automatically close the valve as soon as the pressure passing through the pipe has been reduced below a predetermined point.

Another object of this invention is the production of a simple and efficient means whereby the valve may be allowed to operate and also whereby the valve may be thrown out of operation.

With these and other objects in view, this invention consists of certain novel constructions, combinations and arrangements of parts, as will be hereinafter fully described and claimed.

In the drawings:—Figure 1 is a perspective view of the valve. Fig. 2 is a central vertical section thereof. Fig. 3 is a horizontal section taken on line 3—3 of Fig. 2. Fig. 4 is a detail perspective of the supporting bracket for the diaphragm casing.

By referring to the drawings, it will be seen that 1 designates the inlet valve casing which carries at its upper end a discharge compartment 2. This discharge compartment 2 terminates in a discharge pipe 3 which extends laterally of the discharge compartment 2. A cover plate 4 is bolted upon the upper end of the discharge compartment 2 and is secured thereto by means of bolts 5 passing through the laterally extending flanges 6 formed upon the compartment 2. The cover plate 4 is provided with a centrally arranged upwardly extending collar 7 through which passes the valve stem 8. A packing 9 is placed within the collar 7 and is held in a set position therein by means of a plug 10.

A valve seat 11 is interposed between the discharge compartment 2 and the inlet valve casing 1 and this valve seat is provided with an aperture 12 which aperture is adapted to be closed by means of a valve 13. The valve 13 is supported upon the stem 8

and this stem 8 works through a bridge 14 formed in the inlet valve casing 1. A coil spring 15 is positioned upon the stem 8 and normally exerts an upward pressure upon the valve 13 to force the valve upon its seat when the pressure of the air, gas, or liquid passing through the casing is reduced below a predetermined point.

A diaphragm casing 16 is supported above the inlet casing 1 and this diaphragm casing comprises an upper and a lower section having laterally extending flanges 17 which flanges are firmly held together by means of the bolts 18. The diaphragm casing 16 is suspended from a connecting pipe 19 by means of a T-joint 20. A diaphragm disk 21 is carried within the casing between the flanges 17 of the diaphragm 16. The diaphragm 21 engages the head 22 and this head 22 is connected to the rod 8 and it will be seen that as the pressure passes through the pipe 19 and T-joint 20 into the diaphragm casing 16 the same will act upon the diaphragm disk 21 and force the stem 8 downwardly and remove the valve 13 from the valve seat 11, thereby opening the aperture 12 and allowing the air, gas, or liquid to pass through the casing 1, discharge compartment 2, and discharge pipe 3.

A communicating pipe 23 is secured to the connecting casing 1 and to the supply pipe 19 and this communicating pipe 23 carries a valve 24 so that the passage through the pipe 23 may be closed when so desired. A return pipe 25 is also engaged by the pipe 19 and communicates with the discharge pipe 3 and this pipe 25 also carries a valve 26 which may control the passage through this pipe 25.

A supporting bracket 27 is secured to the top plate 4 near the outer edge thereof and also engages the diaphragm casing 16 under the valve 17 of one of the sections. This bracket 27 is provided with laterally extending feet 28 at each end thereof, which feet constitute means for firmly securing the bracket to both the plate 4 and the diaphragm casing 16. It will be seen that the vertical portion of the bracket 27 will engage the edge of the diaphragm casing 16 and thereby constitute an efficient support or brace for the diaphragm casing and prevent the same from swinging laterally and out of alignment with the plate 4 which, if this lateral swing were allowed, would be likely to cause the valve stem 8 to become

twisted and hence prevent the same from working. This brace 27 will, therefore, constitute a very efficient means for anchoring the diaphragm casing 16 in a set position and relieve the strain from the supply pipe 19.

When the device is in operation, the valve 26 is closed and the air, gas, or liquid which is passing through the apparatus will pass 10 up from the supply casing 1 through the communicating pipe 23 to the pipe 19 and into the diaphragm casing 16 thereby acting upon the diaphragm 21 and forcing the valve 13 out from the valve seat 11 thereby 15 allowing the material, air, gas or liquid, to pass through the valve stem and finally be discharged from the discharge pipe 3.

In case it should be found that it is necessary to repair the valve or apparatus, the 20 valve 24 in the communicating pipe 23 is closed and the valve 26 in the pipe 25 is opened by allowing the pressure within the diaphragm casing 16 to be relieved from the diaphragm and pass out through the pipe 25 and the discharge pipe 3. As the pressure is in this manner relieved, the spring 15 will force the valve 13 to a closed position upon the seat and prevent the further escape of gas, air or liquid passing 30 therethrough.

It should be understood that the present catch or valve, is adapted to be used upon high or low pressure lines for gas, steam, air and water.

35 The principal object of the invention as above stated is to produce an efficient shut-off which will automatically hold the valve in an open position to permit the passage of air, gas, steam or water therethrough when 40 the pressure reaches a predetermined point. It should be further understood that should it be desired to hold the valve in an open position the air, gas, water or steam, which may be used in connection with the valve 45 may be allowed to pass through the pipe 19 into the casing 16, and by securing the desired pressure therein and closing the valves 24 and 26 the pressure may be so retained as to hold the valve 13 from its seat and

produce an open passage through the seat 50 12. The valve 13 may be closed upon its seat 12 by opening the valve 26 for allowing the confined, air steam, gas or water to escape down through the pipe 25 and into the pipe 3, the valve 24 remaining in this instance closed. If it is desired that the valve 55 work automatically the valve 26 is closed and the valve 24 is opened allowing the pressure to act upon the diaphragm 21 and hold the valve open under ordinary pressure.

Having thus described the invention, what is claimed as new, is:—

An automatic valve comprising a casing, 60 a diaphragm casing supported above said first mentioned casing, a diaphragm carried therein, a plunger rod extending through both of said casings, a head engaging the lower face of said diaphragm, a valve disk carried by said plunger rod, means for normally exerting an upward pressure upon said valve disk for holding the same in a closed position, a communicating pipe for constituting a communication between said diaphragm casing and said first mentioned 70 casing, a valve carried by said pipe for opening and closing the passage therethrough, a second pipe, said first mentioned casing comprising an inlet casing and a discharge compartment, said first mentioned 75 pipe communicating with said inlet casing, said second pipe communicating with said discharge compartment, a valve carried by said second pipe for controlling the passage from said diaphragm to said discharge compartment, and said diaphragm casing being suspended by said first and second mentioned pipes, and said valves carried by said first and second pipes adapted to facilitate the confining of material or gas in said dia- 80 phragm casing for holding said valve disk in an open position.

In testimony whereof I hereunto affix my signature in presence of two witnesses.

MILFORD J. McINTYRE.
